UNITED STATES PATENT OFFICE.

CHARLES MARCELUS THOMPSON, OF LEXINGTON, NORTH CAROLINA.

PLOW.

SPECIFICATION forming part of Letters Patent No. 377,653, dated February 7, 1888.

Application filed November 11, 1887. Serial No. 254,918. (No model.)

To all whom it may concern:

Be it known that I, CHARLES MARCELUS THOMPSON, a citizen of the United States, residing at Lexington, in the county of Davidson and State of North Carolina, have invented 5 a new and useful Improvement in Plows, of which the following is a specification.

My invention relates to an improvement in plows; and it consists in the peculiar construction and combination of devices, that will be more fully set forth hereinafter, and particularly pointed out in the claim.

In the accompanying drawings, Figure 1 is a perspective view of portions of a plow embodying my improvements. Fig. 2 is a vertical transverse sectional view of the same taken on the line *xx* of Fig. 1. Fig. 3 is a detached perspective view of the plow-standard. Fig. 4 is a similar view of one of the 20 clip-blocks.

A represents the plow-standard, which is provided at its upper end with a pair of vertical arms, B B', arranged one in front of the other, as shown. On one side of each arm is made a recess, the face of which is provided with a series of transverse ratchet-teeth, the teeth C of the front arm extending downward and the teeth D of the rear arm extending upward, as shown. The front arm, B, is provided with an inclined slot, E, and the rear arm is provided with a vertical slot, F. The recess of the front arm, B, has the rear vertical guide-flange, *b*, and the recess of the rear arm, B', has the front downwardly and forwardly curved guide-flange, *b'*. These guide-flanges coact with the corresponding adjacent edges *b²* *b³* of the teeth C and D, to act as guides for the blocks G and K, hereinafter described. The slot E is inclined downwardly 40 and forwardly, as shown.

G represents a clip-block, which is arranged on the face of the rear arm, B', is adapted to move up and down thereon in a curve, and is provided on its inner side with ratchets H that engage the teeth F. At the lower end of the block G, on the outer side thereof, is a flange, I. The block G has on its front edge the inwardly-standing curved guide-flange *g*, which fits and moves between the guide-flange *b'* and the adjacent curved edge *b³* of the teeth D. 50

K represents a clip-block, which is provided on its inner side with ratchet-teeth L, adapted

to engage the teeth C of the front arm, B, the said block K bearing against one side of said arm and being vertically adjustable thereon. 55 At the upper end of the block K is a flange, M, which projects from the outer side thereof. The block K has on its rear edge the inwardly-standing guide-flange *k*, which fits and moves between the guide-flange *b* and the adjacent edge *b²* of the teeth C.

N represents the cross-beam, of the ordinary construction, which is adapted to bear against the outer side of the blocks K and G, the rear end of the said beam resting on the flange I 65 of the block G, and the upper side of the said beam bearing under the flange M of the plate K. Bolts O are passed transversely through aligned openings in the beam and the blocks and through the slots in the arms B, and to the 70 threaded ends of these bolts are screwed clamping-nuts P.

By means of the curved guide-flange *b'* the inclined slot E, having about the same inclination as the said flange, and too short to need 75 to be curved, and the nuts and bolts, the plow-beam may be set either vertically upward and downward, so that its bolts may be either in the upper or the lower ends of the slots E F, or at corresponding points between said slots, 80 or may be set at an inclination, with the front end pointing either upward or downward, the distance of adjustment ranging from a line running from the upper end of the slot E to the lower end of the slot F to a line running 85 from the upper end of the slot F to the lower end of the slot E. Thus both a good range of vertical adjustment and a large range of inclined adjustment are secured to the plow-beam by the described means. 90

I am aware that plow-beams have been adjusted both vertically or up and down and to inclined positions by means of slotted and toothed extensions of the plow-standard, toothed blocks or plates engaging said extensions, and suitable bolts and nuts, and such I do not claim, broadly. 95

Having thus described my invention, I claim—

The combination, with the plow-standard 100 having the vertical arms B B', the former provided with the vertical rear guide-flange *b*, the downwardly and forwardly inclined slot E, and the downwardly-inclined teeth C, having

the rear guide-edge, b^2 , and the former provided with the front downwardly and forwardly curved guide-flange b' , the vertical slot F, and the upwardly-inclined teeth D, having the front curved guide-edge, b^3 , of the plow-beam N, the clip-block K, having the upwardly-inclined teeth L, the flange M, and rear guide-flange k , the clip-block G, having the downwardly-inclined teeth H, the flange I, and the front curved guide-flange, g , the bolts O, and

nuts P, constructed and arranged substantially as and for the purpose specified.

In testimony that I claim the foregoing as my own I have hereto affixed my signature in presence of two witnesses.

CHARLES MARCELUS THOMPSON.
